MEANS FOR AUTOMATICALLY CONTROLLING THE DRIVING MECHANISM OF STRAIGHT KNITTING MACHINES

Max Richter, West Reading, Pa., assignor to Textile Machine Works, Wyomissing, Pa., a corporation of Pennsylvania

Application March 9, 1935, Serial No. 10,171

12 Claims. (Cl. 66—82)

My invention relates to means for controlling the rate of operation of knitting machines, and particularly to means for automatically controlling a variable-speed driving mechanism for straight or full-fashioned knitting machines.

A full-fashioned stocking ordinarily comprises successively knitted areas of different weights and patterns requiring the knitting machine to be operated at different speeds, as in knitting the welt, the main leg portion, and the plated portions of the leg or heel; a variable-speed brush-shifting motor ordinarily being included as standard equipment in which the brushes are shifted manually relative to the commutator to effect the desired variations in the rate of operation of the machine. However, because such manual operations are not always effected correctly, and depend upon the skill or aptitude of the operator, the value of the variable-speed driving mechanism is considerably diminished.

It is therefore, among the objects of the invention to eliminate the human factor as to the selection of operating speeds of a full-fashioned knitting machine and, so far as such speeds are concerned, to render such machine fully automatic in the production of a stocking unit.

A complete cycle of machine operation, in producing a stocking blank of a certain type, includes operating the machine at an intermediate speed during the knitting of the welt, at a high speed during the knitting of the leg portion proper and at a slow speed during the knitting of reinforced or plated heel areas, each of which speeds has heretofore been effected by the above-mentioned manual shifting of the drive motor brushes, and a temporary slowing of the motor speed effected, during the narrowing of plain areas in the leg portion proper, by the operation of a motor-circuit control switch, without shifting the motor brushes. However, in a reinforced heel area, where the speed is reduced by shifting the brushes and is slow enough to effect narrowing, it is not necessary to operate the above-mentioned motor-circuit control switch.

Another object of the invention is therefore not only to automatically vary the speed of operation of the machine in main steps, as by the above-mentioned shifting of the brushes for knitting the welt, the leg and the heel, but also to have automatic temporary or auxiliary control over such adjusted main speeds, as by automatically operating a switch, as above set forth, for operation during the narrowing of plain areas of the leg, and automatically rendering such switch inoperative or ineffective during the narrowing of a

reinforced area or other area when the motor speed has already been sufficiently reduced, as by shifting the brushes.

Another object of the invention is to render a device of the above indicated character simple and durable in construction, economical to manufacture and effective in its operation.

In attaining the above-mentioned objects, a main pattern device, and an auxiliary pattern unit operated from the cam shaft, generally similar to mechanism of which I am aware, are preferably included, but, since such mechanism, as heretofore employed, is relatively inflexible and expensive as to the adjustment of the auxiliary unit to different patterns, and causes undue wear of, and has other objections relative to, linkage operating between the cam shaft and the unit, it is accordingly a further object to remove such objectionable features whereby the auxiliary pattern unit is rendered considerably more flexible and economical in its pattern adjustment, and the wear, and other adverse features, of the linkage are removed.

With these and other objects in view, which will become apparent from the following description of an illustrative and practical embodiment of the invention shown in the accompanying drawings, my invention resides in the novel elements, features of construction and arrangement of parts in cooperative relationship, as herein-after more particularly pointed out in the claims.

In the drawings:

Figure 1 is a cross-sectional view of a portion of a full fashioned knitting machine, illustrating the invention with respect thereto;

Fig. 2 is a view, similar to a portion of Fig. 1, showing the mechanism employed to actuate the control shaft by which the mechanism of the invention is operated;

Fig. 3 is an end view of a variable speed motor, with the invention applied thereto;

Fig. 4 shows a structure in which various rotating shafts of the machine are connected to, and actuated by, the mechanism shown in Fig. 3;

Fig. 5 is a fragmentary front elevational view of the structure of Fig. 4;

Fig. 6 is an enlarged top view of the mechanism shown in Fig. 3;

Fig. 7 is a diagram, showing the relation of electrical parts and circuits to the apparatus of the invention at one knitting speed;

Figs. 8 to 11, inclusive, are diagrams, each corresponding to a portion of Fig. 7, showing the circuits and relation of parts at successive stages of knitting a full-fashioned stocking; and

Fig. 12 is a diagram of the leg blank of a full-fashioned stocking, together with a pattern chain, as developed or opened out along a straight line in side elevation from its normally looped shape, indicating the areas along the blank in which the speeds of operation are changed, and the corresponding links of the chain by which such changes are effected.

The figures disclose various parts of a Reading full fashioned knitting machine embodying the mechanism and elements of my invention, in which, for clearness, only those parts of the various mechanisms necessary for an understanding of the invention are illustrated; the various other parts and mechanisms, and the manner of operation thereof, being well known in the art, as shown and described in the Reading Full Fashioned Knitting Machine Catalogue, copyright 1929, and published by the Textile Machine Works, Reading, Pennsylvania.

Referring to the drawings, frame members 10, upon which shafts, including a cam shaft 12, are supported, also support front and back rails 13 and 14, front and center beds 15 and 16, and a member 17 which supports an auxiliary-unit control shaft 18, as shown in Fig. 2. The transverse members 13, 14, 15, 16 and 17, with the frames 10, constitute a structure for supporting the operating mechanism proper of a usual full fashioned knitting machine.

Needles 19 are operated in a usual manner by needle and presser levers 20 and 22, respectively, which are actuated by cams fixed to the cam shaft 12. Sinkers 23 and dividers 24 cooperate with the needles 19; the sinkers 23 receiving forward movement from jacks 25, which are slurred forward by slur cams 26 carried by cock boxes 27. The cock boxes are reciprocably mounted on a cock box bar 28. The rearward travel of the sinkers 23, and the forward and rearward movement of the dividers 24, are effected by a catch bar 29, which is operated by a back catch shaft 30, through means of vertical and horizontal shifter arms 32 and 33, respectively, connected to the shaft 30 and to the catch bar 29, as shown. The back catch shaft 30 is actuated by a lever 34, fixed thereto, a cam follower 35 of which engages, and is operated by, a cam carried by the cam shaft 12. The follower 35 is held in yielding engagement with its respective cam member by means of a coil spring 36 that is hooked to the free end of the lever 34, and anchored to the front rail 13, by a hook member 37. A lever 38, secured to the bar 29, operates to move the catch bar 29 into and out of engagement with the sinkers 23. The lever 38 is raised and lowered by a front catch shaft 39 through a linkage including a lifting arm 40 and a lifting lever 42. A roller 43 rotatably mounted on a lever 44, secured to the shaft 39, is operated by a cam on the cam shaft 12.

A front narrowing shaft 45, which carries brackets 46 for supporting narrowing rods 47, to which narrowing fingers 48 are secured, is maintained in parallel relation to a back narrowing shaft 49 by intermediate guide arms 50. Arcuate movement of the shaft 45 relative to bearings 52 is effected by a cam on the cam shaft 12, transmitted to the shaft 45 through a cam follower 53 rotatably mounted on a narrowing lifting lever 54. The lever 54 is pivotally mounted on a pin 55 that is supported by the stationary frame. The lever 54 is also connected to the front narrowing shaft 45 by a link 56.

A motor M, by which the knitting machine is actuated, is supported by a bracket 57 secured to the rail members 13 and 14, as shown in Figs. 1 and 4. A sprocket wheel 58, attached to a hand wheel shaft 59, is rotated by a chain 60, which is driven by the motor M. A second sprocket wheel 62, on the hand wheel shaft 59, rotates a drive shaft 63 through a chain 64, and a sprocket 65 on the shaft 63. A pinion 71, that is disposed on the shaft 63, drives a gear wheel 66 10 which is secured to the cam shaft 12.

The auxiliary-unit control shaft 18, see Fig. 2, by which the various auxiliary-pattern-unit control chains, such as a brush-shifting chain 66, are intermittently actuated, receives its motion from a cam 61, when a supporting lever 100 is moved from beneath a lever 101, thereby permitting a roller 102 to follow the contour of a cam 61. The lever 100 is thus moved by buttons on the conventional main pattern-chain unit or device C, as indicated diagrammatically in Fig. 7. This action transmits oscillatory movement to a member 103, freely mounted on the control shaft by means of an intermediate link 104, whereupon a pawl 105 operates a ratchet wheel 106 secured to the control shaft. A toothed member 61, held in yielding engagement with the ratchet wheel 106 by a spring 68, locks the control shaft 18 against reverse rotation between the intermittent operations of the pawl 105.

The above-described mechanism, as best seen in Fig. 2, wherein there is a linkage including the member 103, the link 104 and the lever 101, between the auxiliary pattern unit, including the chain 66, and the cam shaft 12, is, as heretofore stated, generally similar to a prior mechanism which however, does not have a single-link connection similar to that including the link 104, and does not have a follower-and-cam arrangement similar to that hereof, wherein the follower 102 periodically engages and disengages the cam 61. Instead, the prior device has an eccentric constantly engaged to and operated by, the cam shaft, the continuous motion of which is transmitted, by one linkage, to a position at the auxiliary unit for control, by a second linkage from the main pattern device, to periodically operate the unit, thus including unnecessary structure, occupying undue space, being more expensive, causing unnecessary wear and vibration, and having other disadvantages. Applicant's device reduces this two-linkage arrangement to a single linkage, and removes the constantly-operating linkage, with the advantages manifestly resulting therefrom, which, in combination with the other elements herein set forth, produces an automatic speed-varying mechanism for a straight or full-fashioned knitting machine whereby such machine is substantially improved.

The motor M, preferably of the alternating-current type having shunt characteristics, and which is ordinarily employed to operate a full fashioned knitting machine, has its speed selectively changed by shifting brushes 69 of a commutator 70. The brushes are connected, respectively, to independent phase windings of the stator S, see Fig. 7, and heretofore, have been shifted manually.

Referring to Fig. 3, brush-shifting means operate upon two segmental brush-holder yokes 72 and 73, each of which carries a pair of brushes 69 for contact with the commutator 70. The yokes are movable toward and from each other peripherally of the commutator, and are pivotally connected to projections on separate ro-

tary discs 74 and 75, which are carried by, and are freely turnable on, the motor shaft 76.

To simultaneously move the brushes, an operating member 77 is provided, which carries a pin 78, fixed to its lower end, and is loosely connected to links 79 and 80, Figs. 3 and 4, which are pivotally connected to the discs 74 and 75, respectively. The brush operating member 77 has a slot 82, through which extends a pivot bolt 83 secured to the motor casing. A plate 84, for supporting the member 77 and which is bolted to the motor casing, has an arcuate cam slot 85, through which the pin 78 extends, and in which the pin moves, when the operating member 77 is turned in either direction to shift the brushes. The slot 82, in the operating member 77, permits free longitudinal movement of the latter, when the pin 78 moves in the cam slot 85.

To automatically change the setting of the brushes for regulating the speed of the motor, a control chain 86 is operatively disposed between an idler pulley 87 and an actuator wheel 88 on the control shaft 13. Supported by the transverse bar 17, is a bracket 89 by which a lever 90 is pivotally carried. The lever 90 is connected to the operating member 77, by an intermediate link 92, as shown in Figs. 3 and 4. A chain follower 93, rotatably mounted on the lever 90, is held in yielding engagement with the control chain, by means of the tensioning action of a spring 94 attached to the hook end of the lever 90, and anchored, at its opposite end, to the back rail 14 by a hook clamp 95. This structure permits operation of the member 77, in accordance with the height of the control chain links successively positioned beneath the chain follower.

With a high link 86a positioned, as in Fig. 3, the brushes 69 are shifted to the position shown, whereupon the motor will operate at a low speed. This position is maintained during the process of plating full fashioned hosiery. The motor is operated at high speed, during the fabrication of the main leg portion, when a low link 86b is moved to position as in Fig. 4, by which action the pin 78 is moved to the opposite end of the arcuate slot 85, and the brushes are correspondingly repositioned. Operation of the machine, at medium speed, is effected by movement of a link 86c, of medium size, to a position beneath the roller 93. Medium speed is employed during the knitting of certain areas, as in the welt portion of a stocking. Any desired number of speeds is obtainable by the employment of chain links of various heights.

During the knitting of an unreinforced portion of a stocking, such as the main leg portion, the machine is normally operated at a high speed. To provide for the production of narrowing stitches in such unreinforced portion, the speed of rotation of the cam shaft 12, while in its shifted or narrowing position, must be reduced. To produce this result, a speed reducing switch 99, illustrated diagrammatically in Figs. 7 to 11, inclusive, is operated, by means associated with a main chain motion mechanism C, when the cam shaft is axially shifted.

However, during the formation of plated areas, the speed of operation of the machine is appreciably slower than the speed at which it is operated while knitting unreinforced fabric, and consequently, does not require an additional reduction of speed, or to be affected by the speed-reducing switch, when narrowing the plated portions. Therefore, to nullify the effect of the speed reducing switch, while the machine is already op-

erating at a sufficiently low speed, a safety switch H, see Figs. 1, 4 and 6, is included in the circuit of the speed-reducing switch. The switch H is normally closed when the machine is operating at a high rate of speed, as when the low links 86b of the control chain 86 are positioned as in Fig. 4. However, with the high links 86a in such position, and the resultant reduction of the motor speed, a stud 96, carried by the brush shifting lever 77, coacts with a spring 97 to move a rod 98. This action opens the safety switch H to open the circuit of the speed reducing switch 99, thereby isolating the speed reducing switch, and preventing any effect thereby on the rate of speed of the motor.

When the low cam links 86b move to the position indicated in Fig. 1, the brush shifting lever 77 will be retracted, whereupon the switch H will again be closed, and the speed reducing switch reconditioned, relative to the motor circuit, to affect the latter when the cam shaft is shifted to its narrowing position in a plain-knit course.

The above-described operation may be better understood from a consideration of Figs. 7 to 12, inclusive, in Fig. 7 of which, the motor M is shown as comprising a three-phase rotor R connected to supply-line conductors 202, 203 and 204, and mounted on a shaft 206, also carrying an excitation winding E, and the commutator 70 connected to the winding E, in conventional manner.

It is to be understood that a master switch may be connected to the supply lines at any suitable position, or in conductors 407 which connect the supply lines to the rotor R through slip rings.

The stator S, supplied from the excitation winding E, through the commutator 70 and the brushes 69, comprises separate coils 103 and 108. Resistors 110 and 112 are adapted to be thrown into, and shunted from, the stator circuits as by switches 114 and 115, respectively, connected to a common actuator 117. The latter is biased, as by a spring 118, to hold the switches 114 and 115 in the open positions indicated, in the de-energized condition of a solenoid 119, in which position, the resistors 110 and 112 are shunted out of the circuits of the stator coils 103 and 108.

The solenoid 119 is connected across the supply lines 202 and 203 by a conductor 120, including the safety switch H, and by a conductor 122, including the speed-reducing switch 99, and a push-button switch 123. The switch H is connected, as above set forth, by the rod 98, to the brush-shifting lever 90, which is operated by links on the auxiliary control chain 86. The switch 99 is adapted for operation by buttons on the main pattern chain C, which is conventional in full fashioned knitting machines, and not shown in Figs. 1 to 6, inclusive, but indicated diagrammatically in Figs. 7 to 11, inclusive.

Referring to Figs. 7 and 12, the welt W, in Fig. 12, is indicated as bounded walewise in its folded or finished state by the fold edge 124 and the welt line 125 and, in its open state, before folding over on the edge 124, as bounded by the course 126 and the welt line 125.

The links of the control chain 86 determine the speed sequence at which the machine is operated during the production of a stocking leg blank. The control chain 86 controls the speed of the machine from a line 141, in advance of the first course 126 knitted in the welt, to the

last courses 142 of the blank at the ends of the heel tabs 134.

Prior to starting the first course 126, the control chain 86 is operated from a low speed button 86a to an intermediate speed button 86c, for a distance corresponding to a distance 143, which extends from the line 141 to the course 126, to shift the brushes 69 from a low speed position to an intermediate speed position. The intermediate-speed position is maintained for a distance corresponding to the distance 145, which extends from the course 126 to a course 146.

During this operation, the parts are as indicated in Fig. 7, in which the resistors 112 and 110 are shunted out of the circuits of the stator windings, the switches H and 123 are closed, and the switch 99 is open.

At the course 146, the control chain is again operated, a high speed link 86b shifting the brushes 69 of the motor M, as above set forth and as indicated by the relation of the parts in Fig. 8; this action immediately stepping up the speed of the motor, but leaving the switch H closed, and the switch 99 open, whereby the switches 114 and 115 remain open, and the resistors 110 and 112 are still shunted out of the stator-coil circuits. This position of the parts is maintained for a distance on the blank corresponding to a distance 147, which extends from the course 146 to a course 148.

At the course 148, the control chain is again operated, an intermediate speed link 86c shifting the brushes 69, through the lever 90, as indicated in Fig. 7, this action immediately reducing the speed of the motor, so as to draw the carriers of the alternating mechanism, (not shown), into the knitting field. This position is maintained for a distance 150, which extends from the course 148 to the course 127.

As stated above, the machine then operates, in general, at its high rate of speed in each course for a distance 151 which extends from the course 127 to the course 133, operating at high speed throughout each course.

In courses where the fashioning points are to be inserted, for forming narrower courses, which occurs after a course is produced, the machine is operated at a reduced speed. These reductions of the high speed, occurring in a distance 152, which extends from the course 127 to a course 128, and in the distance 153 extending from the line 130 to the line 132, are accomplished by buttons on the main pattern control chain C, which buttons momentarily close the switch 99.

When the switch 99 is so closed, it completes the circuit of the solenoid 119 from the supply-line conductors 202 and 203, through the switches H and 123, to move the actuator 117 against the action of the spring 118, and to thereby close the switches 114 and 115. This action inserts the resistors 110 and 112 into the circuits of the stator windings 108 and 109, respectively, whereby to reduce the speed of the motor, without changing the positions of the brushes 69 from the high-speed positions thereof, as indicated in Fig. 8.

At the course 133, at which plating begins, a slow-speed link 86a of the auxiliary control chain 86 moves the lever 90 to the positions of the parts indicated in Fig. 10. This action shifts the brushes 69 of the motor M to positions in which the motor operates at a slow, or plating speed, and simultaneously opens the switch H, which up to this time has remained closed throughout the knitting of the welt W and the leg L. This position of the parts is maintained for a dis-

tance 152, which extends from the course 133 to the course 142 of the heel tabs 134. The speed corresponding to this position, being sufficiently slow for both plating and fashioning, it is not necessary to further change the speed at the narrowing courses, so that, a button on the main control chain C, which normally is operative to effect both the fashioning action and a slowing of the speed for such action, is operative only to effect the fashioning action, since, when it closes the switch 99, as indicated in Fig. 11, the switch H is open, and the solenoid 119 is not energized. Thus, when during the knitting of the heel tabs 134, it is necessary to effect narrowing operation, for a distance 154 which extends from the course 136 to the course 137, the speed is not changed at the narrowing courses.

Obviously, many other combinations of links, pattern mechanisms and other elements, as well as other variable-speed motor drive means, may be devised and operated in accordance with the invention, to obtain various combinations of knitting speeds in accordance with any desired pattern, weight of thread or other feature.

The improvements specifically shown and described, by which the above-described results are obtained, may be modified in various ways without departing from the spirit and scope of the invention as herein disclosed and claimed.

I claim:

1. A full-fashioned knitting machine including a variable-speed drive mechanism, control means therefor, a cam shaft for operation by the drive mechanism, means responsive to axial shifting of the cam shaft for affecting the speed of the drive mechanism, means for governing the operation of said speed affecting means, and pattern means for simultaneously operating said control and said governing means.

2. A knitting machine comprising knitting mechanism, pattern mechanism, means for actuating the knitting mechanism to knit a fabric continuously through a plurality of areas in which the knitting mechanism is operated at different rates, means automatically operative in accordance with operation of the pattern mechanism for varying the rate of operation of the actuating means during the patterning of an area thereby, and means automatically responsive to operation of the machine for varying the rate of operation of the actuating means, and nullifying the effect of said first automatic means, during the patterning of another area by the pattern mechanism.

3. A full-fashioned knitting machine comprising knitting mechanism, narrowing mechanism, means for actuating the knitting mechanism to knit a stocking blank continuously through a plurality of areas in which the knitting mechanism is operated at different rates, means automatically operative in accordance with operation of the narrowing mechanism for varying the rate of operation of the actuating means during narrowing of a plain area, and means automatically operative in accordance with knitting movement of the blank for varying the rate of operation of the actuating means during the knitting of a plated area and nullifying the effect of said first automatic means during the narrowing of a plated area.

4. In a knitting machine, actuating means including a brush-shifting motor, an auxiliary pattern unit for shifting the brushes of the motor, resistor means, and a main pattern unit for controlling the insertion of the resistor means

into the stator circuit of the motor and the withdrawal of the resistor means from the stator circuit to affect the speed of the motor independently of the brushes.

5. In a knitting machine, loop-forming mechanism, actuating means including a three-phase alternating-current motor embodying a stator, a commutator and shiftable brushes for the commutator, a resistor, a switch for inserting the resistor into, and excluding it from, the stator circuit, pattern mechanism, and means responsive to operation of the actuating means and controlled by the pattern mechanism for controlling both the shifting of the brushes and the operation of the switch.

6. A full-fashioned knitting machine including a drive mechanism embodying a variable-speed motor, control means therefor, a cam shaft rotated by the drive mechanism, an auxiliary shaft intermittently rotated by the cam shaft, a speed reducing switch operative by axial shifting of the cam shaft, a safety switch for controlling the operation of the speed reducing switch, and a pattern chain carried by the auxiliary shaft for simultaneously operating the variable-speed motor control means and the safety switch.

7. In combination, in a full-fashioned knitting machine, a knitting mechanism, actuating means therefor comprising a motor including brushes shiftable to vary the rate of operation thereof, narrowing mechanism, means in the circuit of the motor and operative in accordance with operation of the narrowing mechanism for controlling the rate of operation of the motor, means for determining the rate of operation of the motor embodying means for shifting the brushes and controlling said first control means, a cam shaft, means including a cam on the shaft for actuating the brush-shifting means, and means including a pattern mechanism for controlling the actuation of said rate-determining means by the cam.

8. In a knitting machine, knitting mechanism, means including an electric motor for actuating said knitting mechanism, said motor including a commutator and brushes for the commutator, means for shifting the brushes, means for actuating said brush-shifting means to vary the speed of the motor, means for varying the speed of the motor independently of said brush-shifting means, and means including pattern-control means for controlling said brush-shifting actuating means at one time to vary the speed of the motor and, at another time, simultaneously to maintain the brush-shifting means inactive and to control said independent speed-varying means to vary the speed of the motor.

9. In a knitting machine, an alternating-current motor including a rotor carrying an excitation winding and a commutator, a stator, means including brushes cooperating with the commutator for connecting the excitation winding to the stator, means for shifting the brushes to vary the speed of the rotor, an auxiliary pattern unit for controlling the brush-shifting means, resistor means, switch means for throwing the resistor means into and out of the stator circuit, electro-responsive means for actuating said switch means, a switch controlled by the brush-shifting means for opening and closing the circuit of said electro-responsive means, a main pattern unit, and a switch controlled by the main pattern unit for opening and closing the circuit of said electro-responsive means.

10. In a knitting machine, an alternating-current motor including a rotor carrying an excitation winding and a commutator, a stator, means including brushes cooperating with the commutator for connecting the excitation winding to the stator, means for shifting the brushes to vary the speed of the rotor, means responsive to operation of the machine for controlling the brush-shifting means, impedance means, means for inserting the impedance means into, and withdrawing it from, cooperative relation to the stator circuit, electro-responsive means for actuating said inserting and withdrawing means, means controlled by the brush-shifting means for energizing and deenergizing the circuit of said said electro-responsive means, and means responsive to operation of the machine for energizing and deenergizing the circuit of said electro-responsive means.

11. In a machine for knitting a full-fashioned stocking, knitting mechanism, narrowing mechanism, actuating means including an electric motor including a commutator and brushes for the commutator, shifting of the brushes on the commutator causing the motor to operate at different speeds, pattern means, means controlled by the pattern means for shifting the motor brushes to operate the machine at an intermediate speed during the knitting of the welt, at a high speed during the knitting of the leg portion and at a slow speed during the knitting of reinforced or plated heel areas, means for affecting the motor circuit to control the speed of the motor independently of the brushes, and a circuit making-and-breaking device for controlling said last named means, the pattern means controlling the circuit making-and-breaking device to temporarily reduce the speed of the motor independently of the position of the brushes during narrowing in the leg area, and to prevent varying the speed of the motor independently of the brushes during narrowing in the heel area.

12. A full-fashioned knitting machine comprising knitting mechanism, means including an electric motor for actuating the knitting mechanism to knit a stocking blank continuously through the welt, the leg and a heel having reinforced tabs, the motor including a commutator and brushes shiftable thereon to vary the motor speed, means in the motor circuit to vary the motor speed, narrowing mechanism for operation by the actuating means, means for automatically controlling the narrowing mechanisms during the knitting operation to effect successively spaced narrowing operations adjacent to the top and bottom of the leg, respectively, and in the heel, brush-control means automatically responsive to operation of the actuating means for shifting the brushes to operate the motor at an intermediate speed during the knitting of the welt, at a high speed during the knitting of the leg and at a low speed during the knitting of the heel, and means operative in accordance with operation of the narrowing mechanism for controlling said motor circuit motor-speed varying means to operate the motor at slow speeds during the narrowing operations in the leg and rendering said motor-circuit motor-speed varying means ineffective to affect the motor speed during the knitting and narrowing operation of the heel.

MAX RICHTER.
